UNITED STATES PATENT OFFICE

2,101,656

REFRIGERATING MACHINE

Christian Steenstrup, Schenectady, N. Y., assignor to General Electric Company, a corporation of New York

Application January 22, 1935, Serial No. 2,912

18 Claims. (Cl. 62—99)

My invention relates to refrigerating machines. In many types of refrigerating machines and particularly in those designed for domestic use, it is necessary to make provision for the storage 5 and preservation of a large variety of perishable articles and it is also desirable to provide apparatus for freezing ice and the like therein. Some perishable articles, such as meat, which are to be stored for a relatively long period of time can 10 be most easily preserved by maintaining them at a temperature below 32° F. Other articles, such as milk, should be maintained at a somewhat higher temperature. In addition, it is necessary to make provision for the storage of vegetables 15 of various kinds, which also need not be kept at a temperature below 32° F., but which are subject to rapid deterioration through dehydration unless kept under proper conditions of temperature and humidity. In commercial cold storage 20 establishments it is possible to provide a large number of separate refrigerating machines, each being designed to maintain the particular temperature and humidity conditions required by the particular variety of articles to be preserved 25 therein. It is obvious, however, that such an arrangement is not economically feasible for domestic use or for use in small restaurants and the like. Limitations of space and cost make it necessary that the refrigerating apparatus for 30 installations of this type contain but a single refrigerating device and that the entire apparatus be preferably housed in a single cabinet.

Refrigerating machines of the primary-secondary type are particularly adapted for the purpose described. In refrigerating machines of the primary-secondary type a primary refrigerant system or circuit is provided which includes a primary evaporator supplied with liquid refrigerant from a suitable source or refrigerant 35 circulating device of any of the well known types. The secondary refrigerant system or circuit also includes an evaporator. The refrigerant passages of the two refrigerant circuits are not in communication with each other, but portions of 40 the two refrigerant circuits are, however, arranged in heat exchanged relationship, so that the primary evaporator abstracts heat from the refrigerant contained in the secondary refrigerant circuit. Because of the independence of the 45 circulatory systems of the two refrigerant circuits it is possible to maintain the evaporator contained in each circuit at a different temperature from the other.

It is an object of my invention to provide a 50 refrigerating machine having a single refrigerant

circulating device and in which a plurality of noncommunicating compartments mounted as a unitary structure are available for storing a variety of perishable articles under different conditions of temperature and humidity. 5

It is a further object of my invention to provide a refrigerating machine of the primary-secondary type for the purpose described which is economical to manufacture, assemble and operate and which is rugged in construction. 10

Further objects and advantages of my invention will become apparent as the following description proceeds and the features of novelty which characterize my invention will be pointed out with particularity in the claims annexed to 15 and forming a part of this specification.

For a better understanding of my invention reference may be had to the accompanying drawings, in which Fig. 1 is a front elevation partly in section of a refrigerating machine embodying 20 my invention; Fig. 2 is a side elevation partly in section of the refrigerating machine shown in Fig. 1; Fig. 3 is an exploded view of the refrigerating machine shown in Fig. 1 the lower portion thereof being partly cut away; and Fig. 4 is a 25 sectional detail view of a modified form of heat conducting member which may be used in the refrigerating machine shown in Figs. 1, 2, and 3.

Referring to the drawings, in Fig. 1 I have shown a refrigerating machine embodying my 30 invention having a smooth walled rectangular cabinet made up of separable upper and lower portions 1 and 2, respectively. The upper portion 1 of the cabinet is provided with an outer sheet metal shell 3 and has a rectangular food 35 storage or freezing compartment 4 formed therein. The side walls and top of the freezing compartment 4 are surrounded by heat insulation 5. The lower portion 2 of the cabinet, which supports the upper portion 1, is provided with an 40 outer sheet metal shell 6, and has a rectangular food storage or cooling compartment 7 formed 45 therein. The side walls and bottom wall of the compartment 7 are surrounded by heat insulation 8. The metal shell 3 is provided with a 50 downwardly extending rectangular flange 3a, which surrounds the upper periphery of the metal shell 6, thereby forming a firm telescopic joint between the upper and lower portions 1 and 2 respectively of the cabinet, and effectively prevents their relative lateral displacement. A 55 rectangular rubber gasket 9 rests on the inturned rectangular upper edge of the metal shell 6 and is firmly pressed thereon by the weight of the upper portion 1 of the cabinet. An air-tight

55

joint is thus formed between the upper and lower portions of the cabinet and in that way the ingress of air to the space between them is prevented. It is necessary thus to exclude moisture-laden air from the space between the walls of the cabinet containing insulation both to prevent the formation of frost therein and also to prevent the deposit of moisture in the insulation, because the insulation is usually made of some dry fibrous material, the heat insulating properties of which are radically reduced when it absorbs a substantial amount of moisture.

10 The freezing compartment 4 is provided with a metallic liner 11 cooperating with a corrugated metal sheet 12, which surrounds the liner 11 on four sides thereof to form a refrigerant evaporator 10 associated with the freezing compartment 4. The inwardly projecting ridges of the corrugations formed in the sheet 12 are in contact 20 with the smooth sheet metal liner 11 and are welded, brazed or otherwise secured thereto throughout their length. The transverse corrugations in the plate 12 cooperate with the liner 11 to form refrigerant passages 13 which are connected at their opposite ends with a header 14, the latter being formed by opposed portions of the liner 11 and the metal sheet 12.

15 An evaporator structure consisting of a smooth sheet and a corrugated sheet, the ends of the sheets forming a header, and the two sheets being welded or brazed together between the corrugations forms no part of my present invention but is described and claimed in my application S. N. 389,050, filed August 28, 1929, and assigned to 25 the General Electric Company, the assignee of my present invention.

20 Gaseous refrigerant is compressed by a motor driven compressor contained in an hermetically sealed casing 15 and supplied through conduit 16 to an air cooled condenser 17 which surrounds the casing 15, the condenser and casing being cooled by natural draft. Liquefied refrigerant leaves the condenser 17 through a conduit 18 and passes through a flow controlling float valve 19 flowing therefrom through a conduit 20 to an inlet 21 in the side of the evaporator 10. The liquid refrigerant is thus injected into the evaporator 10 by the inlet 21 from the conduit 20 and recirculates through the refrigerant passages 13 25 of the evaporator 10 and its header 14. Liquid refrigerant in the refrigerant passages 13 is vaporized by the absorption of heat from articles contained in the freezing compartment 4 and the upper wall of the lower compartment 7 and the bubbles of vaporized refrigerant flow there- 30 through to the header 14 where they are collected above the level of the liquid refrigerant therein. The vaporized refrigerant collected in the header 14 is returned to the compressor in the casing 15 35 through a suction line 22, which is connected to the top of header 14 and above the level of the liquid refrigerant therein.

40 The cooling compartment 7 has a metallic liner 26, which is surrounded on four sides by a metal sheet 27 provided with transverse corrugations cooperating with the liner 26 to form the refrigerant passages of a secondary evaporator or container 25 associated with the cooling compartment 7 and constituting a secondary refrigerant system. The inwardly extending ridges of the corrugations formed in the sheet 27 are in contact with the smooth sheet metal liner 26 and are welded, brazed or otherwise secured thereto throughout their length. A body of liquid vaporizable refrigerant is contained in the secondary

45 evaporator 25 substantially filling the lower and side portions thereof, and as it absorbs heat from articles contained in the cooling compartment 7 it is vaporized, the bubbles of vaporized refrigerant passing upwardly through the vertical refrigerant passages of the evaporator 25 and being collected in the upper horizontal portion 28 thereof.

50 The top of the secondary evaporator 25 and the bottom of the primary evaporator 10 are arranged adjacent the opening in the interior of the refrigerator cabinet between the freezing compartment 4 and the cooling compartment 7 and a corrugated resilient metal plate 29 is placed between the top of the secondary evaporator 25 and the bottom of the primary evaporator 10, which plate together with the top of the secondary evaporator 25 and the bottom of the primary evaporator 10 form a dividing wall between the freezing compartment 4 and the cooling compartment 7. The corrugated metal plate 29 thus forms a resilient heat conducting member between the primary and secondary evaporators to facilitate heat exchange between the two refrigerant circuits.

55 As best shown in Fig. 3, the corrugations in the metal plate 29 are arranged transversely of the parallel corrugations in sheets 12 and 27 in order to improve the contact between adjacent surfaces thereof. The clearance between the 30 sheets 12 and 27 is made slightly less than the unstressed depth of the corrugations in the metal plate 29, so that when the respective parts are in position the metal plate 29 will be somewhat flattened, accordion fashion, thus insuring a tight 35 contact between the abutting surfaces of sheets 12 and 27 and the metal plate 29. I have also found it advantageous to cover these abutting surfaces with a thin film of grease which improves the contact and aids in preventing the 40 formation of frost therebetween.

45 Heat is transferred from the vaporized refrigerant, which collects in the upper refrigerant passages of the secondary evaporator 25 to the liquid refrigerant in the lower portion of the primary evaporator 10 through the resilient heat conducting plate 29 and the adjacent walls of the evaporator. Refrigerant thus cooled in the upper refrigerant passages of secondary evaporator 25 is liquefied and then drains back to the 50 lower portion thereof where it again absorbs heat from articles stored in the cooling compartment and is vaporized. As best shown in Figs. 1 and 3, the top portion of evaporator 25 slopes to one side so as to facilitate the return flow of liquid refrigerant therefrom to the lower portion of the 55 evaporator.

60 The heat conductivity of the plate 29 is proportioned by varying its constituent material, the area of its contact with the corrugated sheets 12 and 27, or the thickness of the plate so that a limited amount of heat will be transferred from the secondary evaporator 25 to the primary evaporator 10. If the secondary evaporator 25 is placed in direct heat conducting relation with the primary evaporator 10, their adjacent surfaces will remain at approximately the same temperature. It is desirable, however, that the temperature of the primary evaporator 10 be substantially lower than that of the secondary 65 evaporator 25 for the proper operation of the machine. The primary evaporator 10 should be maintained at a temperature of from 0 to 10° F., while the temperature of the secondary evaporator 25 should be maintained about 32° F. 70 75

The particular significance of the temperature of these evaporators with relation to the proper preservation of the materials contained in the compartments 4 and 7, respectively, is pointed out more in detail below. The desired difference in temperature between the evaporators 10 and 25 may also be attained by proportioning the amount of liquid refrigerant contained in each of them. If sulphur dioxide, for example, is used as the refrigerant in both evaporators, the amount of liquid refrigerant in the secondary evaporator 25 may be proportioned with respect to its total volume in such manner that only the lower portions of the refrigerant circulatory passages of the secondary evaporator 25 formed between the sheets of metal 26 and 27 are filled with liquid refrigerant. Then, since the portion of the evaporator containing liquid refrigerant performs the major part of the cooling, the total amount of heat dissipated from the cooling compartment 7 is decreased and the average temperature prevailing in the cooling compartment is increased.

I have thus provided means for abstracting heat from the contents of both the freezing and cooling compartments 4 and 7 in such manner that each is maintained at its appropriate temperature and yet the apparatus required includes only one refrigerant circulating device, namely the motor driven compressor in casing 15, and the entire apparatus is compactly arranged in a unitary structure.

In Fig. 4 I have shown a modified form of resilient heat conducting member 30, which may be substituted for the resilient corrugated plate 29 described above. The resilient heat conducting member 30 comprises a body of thermally conducting masses 31, which may be metallic shot of spherical configuration made of lead or steel, or the like, and which are bonded together by a resilient matrix of rubber, or some similar binding material. The metallic spheres are so arranged that their adjacent peripheral portions are in direct contact thus forming a heat transfer path between the sheets 12 and 27 while the rubber matrix allows a sufficient resilience in the member 30 that its upper and lower surfaces will form a tight contact with the adjacent irregular surfaces of the sheets 12 and 27. It will be obvious to those skilled in the art that other forms of resilient heat conducting members may be substituted for the forms which I have illustrated. The amount of heat transferred through the member 10 may be limited, for the purposes noted above, by varying the number of thermally conducting masses 31 and the distance between them.

All of the refrigerating apparatus including any moving parts is contained in the upper portion 1 of the cabinet. Since these are the parts which may most advantageously be separately assembled, the manufacture and repair of the refrigerating machine is greatly facilitated, as this upper portion 1 of the cabinet may be easily attached and removed from the lower portion 2 for purposes of assembly and repair. The separable arrangement of the upper and lower portions 1 and 2 of the cabinet and the corrugated plate 29 is best shown in Fig. 3. The secondary evaporator 25 is arranged to be easily inserted or removed through the opening in the top of insulating casing 8 thus further taking advantage of the separable construction of the cabinet.

As will be seen from an inspection of Fig. 2, the freezing and cooling compartments 4 and 7 are

provided with aligned openings 32 and 33, respectively, in the front walls thereof which may be closed by the doors 34 and 35. The openings 32 and 33 provide a convenient means of access to their respective compartments. Cuts of meat or other perishable articles which should be maintained at a temperature of below 32° F., usually within the range of from 0° F. to 10° F., in order to properly preserve them for a relatively long period of time, may be placed in the freezing compartment 4. Trays of water to be frozen, ingredients for ice cream and the like, may also be placed in the freezing compartment 4. The cooling compartment 7 is provided with horizontal shelves 36 which are supported on the projections 37 formed on the interior lateral walls of the metallic liner 26. Bottles of milk, vegetables and the like, may be preserved in the cooling compartment 7 at a temperature above 32° F. and below 50° F. and I have found 40° F. to be a desirable average operating temperature. It will be noted that the secondary evaporator 25 surrounds four walls of the cooling compartment 7 thus providing a relatively large cooling area in proportion to the cubic contents of the cooling compartment 7. Thus, it is possible to cool the contents of compartment 7 with a relatively small temperature differential, that is in the order of about 5° F., between the compartment and the secondary evaporator 25. The use of an evaporator surrounding at least four walls of the compartment 7 has a further advantage in maintaining a small temperature differential between the contents of the compartment and the evaporator which cools it. This advantage results from the fact that heat leaking into the compartment 7 through the insulated walls 8 thereof is intercepted on at least four sides by the evaporator 25. This heat, which leaks into the cabinet, is thus absorbed directly by the evaporator surfaces. In the case of a conventional type of refrigerator in which a large compartment is cooled by a relatively small and compact evaporator, heat, which leaks into the cooling compartment through the walls thereof, must be transferred through the air contained in the compartment to the evaporator thus further increasing the temperature differential between the air in the compartment and the evaporator. By means of the arrangement described, the interior walls of the evaporator 25 may be maintained at a temperature above 32° F. and thus frosting of the walls of the evaporator 25 and hence dehydration of the contents of the cooling compartment 7, is avoided. Dehydration of vegetables and similar articles is of prime importance to their proper preservation, since dehydration is one of the principal causes of their wilting and taking on an unpalatable appearance. In the illustrative form of my invention the primary evaporator 10 is also provided with a relatively large cooling area in proportion to the cubic contents of the freezing chamber 4 in order to reduce the frosting thereof. That is, if we assume a fixed rate of dehydration, the thickness of the layer of frost formed on the evaporator 10 will be inversely proportional to its area.

While I have shown a particular embodiment of my invention in connection with a compression refrigerating machine, I do not desire my invention to be limited to the particular construction shown and described and I intend in the appended claims to cover all modifications within the spirit and scope of my invention.

What I claim as new and desire to secure by Letters Patent of the United States is:

1. A refrigerating machine comprising a heat insulated cooling compartment, a separable heat insulated freezing compartment mounted adjacent said cooling compartment, said compartments being mounted as a unitary structure and the exterior wall of said compartments defining a smooth walled rectangular cabinet, means including a refrigerant evaporator having a portion thereof associated with said freezing compartment for cooling the contents thereof to a relatively low temperature, means including a second refrigerant evaporator having a portion thereof associated with said cooling compartment for cooling the contents thereof to a temperature above freezing, and means including a portion of the first mentioned evaporator for abstracting heat from refrigerant contained in said second evaporator.
2. A refrigerating machine comprising a heat insulated cooling compartment and a heat insulated freezing compartment, said compartments being mounted in separable superposed relationship and the exterior walls of said compartments defining a smooth-walled rectangular cabinet, means including a refrigerant evaporator having a portion thereof associated with said freezing compartment for cooling the contents thereof to a relatively low temperature, means including a second refrigerant evaporator having a portion thereof associated with said cooling compartment for cooling the contents thereof to a temperature above freezing, and means including a portion of the first mentioned evaporator for abstracting heat from refrigerant contained in said second evaporator.
3. A refrigerating machine comprising a heat insulated cooling compartment, a separable heat insulated freezing compartment supported on the top of said cooling compartment and cooperating therewith to form a unitary cabinet structure, means including a refrigerant evaporator having a portion thereof associated with said freezing compartment for cooling the contents thereof to a relatively low temperature, said evaporator having a second portion thereof extending along the bottom of said freezing compartment, and means including a secondary refrigerating apparatus having a portion thereof associated with said cooling compartment for cooling the contents of said cooling compartment to a temperature above freezing, said secondary refrigerating apparatus having a refrigerant passage extending along the top of said cooling compartment in heat exchange relationship with the adjacent portion of said first mentioned evaporator.
4. A refrigerating machine comprising heat insulated cooling and freezing compartments, means including a refrigerant evaporator having a portion thereof associated with said freezing compartment for cooling the contents thereof to a relatively low temperature, said evaporator having a second portion thereof extending along the exterior side of one of the walls of said freezing compartment, means including a secondary refrigerating apparatus having a portion thereof associated with said cooling compartment for cooling the contents thereof to a temperature above freezing, said secondary refrigerating apparatus having a refrigerant passage extending along the exterior side of a wall of said cooling compartment adjacent the exposed portion of said first mentioned evaporator, and means including a resilient heat conducting member for transmitting heat from said passage of said secondary refrigerating apparatus to said exposed portion of said first mentioned evaporator.
5. A refrigerating machine comprising a heat insulated cooling compartment, a separable heat insulated freezing compartment mounted on top of the said cooling compartment, means including a refrigerant evaporator having a portion thereof associated with said freezing compartment for cooling the contents thereof to a relatively low temperature, said evaporator having a second portion thereof extending along the bottom of said freezing compartment, means including a secondary refrigerating apparatus having a portion thereof associated with said cooling compartment for cooling the contents of said cooling compartment to a temperature above freezing, said secondary refrigerating apparatus having a refrigerant passage extending along the top of said cooling compartment, and means including a corrugated sheet of resilient heat conducting material for transmitting heat from said secondary refrigerating apparatus refrigerant passage to the adjacent portion of said first mentioned evaporator.
6. A refrigerating machine comprising a heat insulated cooling compartment, a separable heat insulated freezing compartment mounted on the top of said cooling compartment, means including a refrigerant evaporator having a portion thereof associated with said freezing compartment for cooling the contents thereof to a relatively low temperature, said evaporator having a second portion thereof extending along the bottom of said freezing compartment, means including a secondary refrigerating apparatus having a portion thereof associated with said cooling compartment for cooling the contents thereof to a temperature above freezing, said secondary refrigerating apparatus having a refrigerant passage extending along the top of said cooling compartment, and means including a resilient member comprising a body of metallic spheres bonded together by rubber for transmitting heat from said secondary refrigerating apparatus refrigerant passage to the adjacent portion of said first mentioned evaporator.
7. A refrigerating machine comprising separable freezing and cooling compartments mounted adjacent each other, a rectangular metallic liner for said freezing compartment, a refrigerant evaporator extending about at least four sides of said liner, an insulating casing surrounding said freezing compartment and having an aperture therein exposing a portion of an exterior side of said refrigerant evaporator, a rectangular metallic liner for said cooling compartment, a second refrigerant evaporator extending about at least four sides of said last mentioned liner, an insulating casing surrounding said cooling compartment and having an aperture therein adjacent the aperture in the first mentioned insulating casing exposing a portion of an exterior side of said secondary refrigerant evaporator, and means including a resilient heat conducting member for transmitting heat between the exposed portions of said evaporators.
8. A refrigerating machine comprising separable freezing and cooling compartments mounted adjacent each other, said freezing compartment having a rectangular metallic liner, a corrugated metallic sheet surrounding said liner on at least four sides, said liner and said sheet defining a refrigerant passage between the juxtaposed faces thereof, an insulating casing surrounding said freezing compartment and having an aperture therein exposing a portion of an exterior surface of said refrigerant passage, a rectangular metallic

- liner for said cooling compartment, a corrugated metallic sheet surrounding said last mentioned liner on at least four sides, said liner and said last mentioned sheet defining a refrigerant passage between juxtaposed faces thereof, an insulating casing surrounding said cooling compartment and having an aperture therein adjacent the first mentioned aperture and exposing a portion of an exterior surface of said last mentioned refrigerant passage, and means including a resilient heat conducting member for transmitting heat between the exposed portions of said refrigerant passages. 5
9. In a refrigerating apparatus having a primary refrigerant evaporator and a secondary refrigerant evaporator containing a body of liquid refrigerant, means for supplying liquid refrigerant to said primary evaporator and means including a resilient heat conducting member arranged between said primary and secondary evaporators in heat exchange relationship therewith for transferring heat from the refrigerant in said secondary evaporator to the refrigerant in said primary evaporator. 10
10. In a refrigerating apparatus having a primary refrigerant evaporator and a secondary refrigerant evaporator containing a body of liquid refrigerant, means for supplying liquid refrigerant to said primary evaporator, and means including a resilient heat conducting member comprising a body of thermally conducting masses arranged between said primary and secondary evaporators in heat exchange relationship therewith for transferring heat from the refrigerant in said secondary evaporator to the refrigerant in said primary evaporator. 15
11. In a refrigerating apparatus having a primary refrigerant evaporator and a secondary refrigerant evaporator containing a body of liquid refrigerant, means for supplying liquid refrigerant to said primary evaporator, and means including a corrugated sheet of resilient heat conducting material arranged between said primary and secondary evaporators in heat exchange relationship therewith for transferring heat from the refrigerant in said secondary evaporator to the refrigerant in said primary evaporator. 20
12. In a refrigerating apparatus having a primary refrigerant evaporator and a secondary refrigerant evaporator containing a body of liquid refrigerant, means for supplying liquid refrigerant to said primary evaporator, and means including a resilient heat conducting member comprising a body of metallic spheres bonded together by rubber arranged between said primary and secondary evaporators in heat exchange relationship therewith for transferring heat from the refrigerant in said secondary evaporator to the refrigerant in said primary evaporator. 25
13. A refrigerating machine comprising heat insulated freezing and cooling compartments having an opening therebetween, means including a primary evaporator having a portion thereof associated with said freezing compartment for cooling the contents thereof to a relatively low temperature, said primary evaporator having a further portion thereof extending across said opening, means including a secondary refrigerating apparatus provided with a secondary evaporator having a portion of relatively large area associated with said cooling compartment for cooling the contents of said cooling compartment to a temperature above freezing and for maintaining a relatively small differential in temperature between said secondary evaporator and the contents of said cooling compartment to prevent dehydration thereof, said secondary refrigerating apparatus also including a refrigerant passage in heat exchange relationship with the portion of said primary evaporator extending across said opening between said compartments. 30
14. A refrigerating machine comprising a heat insulated cooling compartment, a separable heat insulated freezing compartment supported on top of said cooling compartment and cooperating therewith to form a unitary cabinet structure, means including a refrigerant evaporator having a portion thereof associated with said freezing compartment for cooling the contents thereof to a relatively low temperature, said evaporator having a second portion thereof extending along the bottom of said freezing compartment, means including a secondary refrigerating apparatus having a portion thereof associated with said cooling compartment for cooling the contents of said cooling compartment to a temperature above freezing, said secondary refrigerating apparatus having a refrigerant passage extending along the top of said cooling compartment, and means transferring a limited amount of heat from said secondary evaporator to said primary evaporator for maintaining said secondary evaporator at a relatively higher temperature than said primary evaporator. 35
15. A refrigerating machine comprising a heat insulated cooling compartment and a heat insulated freezing compartment, said compartments being mounted in separable superposed relationship with the exterior vertical walls thereof arranged in alignment, means including a peripheral flange extending about the edge of one of said compartments adjacent the other of said compartments for preventing lateral displacement between said compartments, means including a refrigerant evaporator having a portion thereof associated with said freezing compartment for cooling the contents thereof to a relatively low temperature, means including a second refrigerant evaporator having a portion thereof associated with said cooling compartment for cooling the contents thereof to a temperature above freezing, and means including a portion of the first mentioned evaporator for abstracting heat from refrigerant contained in said second evaporator. 40
16. A refrigerator comprising a heat insulated cabinet, means for dividing the interior of said cabinet into a plurality of food storage compartments to be cooled to different temperatures, means including a primary refrigerating system for cooling one of said compartments to a relatively low temperature, means including a secondary refrigerating system for cooling the other of said compartments to a relatively higher temperature, and means including a portion of said primary refrigerating system and a portion of said secondary refrigerating system arranged in heat exchange relationship and forming at least a portion of said dividing means for transferring heat from said secondary refrigerating system to said primary refrigerating system. 45
17. A refrigerator comprising a heat insulated cabinet, means for dividing the interior of said cabinet into a plurality of food storage compartments to be cooled to different temperatures, means including a primary refrigerating system for cooling one of said compartments to a relatively low temperature, means including a secondary refrigerating system for cooling the other of said compartments to a relatively higher temperature. 50

perature, and means including a portion of said primary refrigerating system forming at least a portion of said dividing means for transferring heat from said secondary refrigerating system to said primary refrigerating system.

18. A refrigerator comprising a heat insulated cabinet, means for dividing the interior of said cabinet into a plurality of food storage compartments to be cooled to different temperatures, 10 means including a primary refrigerating system

for cooling one of said compartments to a relatively low temperature, means including a secondary refrigerating system for cooling the other of said compartments to a relatively higher temperature, and means including a portion of said secondary refrigerating system forming at least a portion of said dividing means for transferring heat from said secondary refrigerating system to said primary refrigerating system. 5
